DESIGN FOR A SAFETY ZONE COLUMN

George Littleford, Cincinnati, Ohio

Application December 14, 1934, Serial No. 54,423

Term of patent 3½ years

To all whom it may concern:

Be it known that I, George Littleford, a citizen of the United States, residing at Cincinnati, in the county of Hamilton and State of Ohio, have invented a new, original, and ornamental Design for a Safety Zone Column, of which the following is a specification, reference being had to the accompanying drawing, forming part thereof.

Figure 1 is a front elevation of a safety zone column showing my new design.

Figure 2 is a side elevation of a safety zone column.

I claim:

The ornamental design for a safety zone column, as shown.

GEORGE LITTLEFORD.
